UNITED STATES PATENT OFFICE.

JULIUS B. WANTZ, OF CHICAGO, ILLINOIS, ASSIGNOR TO VICTOR ELECTRIC COMPANY, OF CHICAGO, ILLINOIS, A CORPORATION OF ILLINOIS.

SURGICAL EYE-MAGNET APPLIANCE.

No. 843,979.

Specification of Letters Patent.

Patented Feb. 12, 1907.

Application filed November 24, 1906. Serial No. 344,830.

To all whom it may concern:

Be it known that I, JULIUS B. WANTZ, a citizen of the United States, residing at Chicago, in the county of Cook and State of Illinois, have invented a new and useful Improvement in Surgical Eye-Magnet Appliances, of which the following is a specification.

My invention relates to an improvement in the class of surgical appliances involving a powerful electromagnet adapted to be presented to the eyeball of a patient and when energized extract therefrom magnetic material, such as metal splinters, which may have 15 penetrated into it.

The more important objects of my invention are to provide a construction of such an appliance which shall adapt it to be conveniently moved into position for use on the patient, and more particularly to permit required accuracy and nicety of adjustment of the electromagnet with relation to the eyeball to be operated upon. These objects are accomplished by the construction illustrated 25 in the accompanying drawings, in which—

Figure 1 is a view in elevation of a surgical eye-magnet appliance containing my improvements; Fig. 2, a broken section taken at the line 2 on Fig. 1 viewed in the direction 30 of the arrow and enlarged; Fig. 3, a broken section taken at the line 3 on Fig. 2 and viewed in the direction of the arrow; Fig. 4, a section taken at the line 4 on Fig. 3 and viewed in the direction of the arrow; and Fig. 5, a perspective view of a bracket detail.

A hollow standard 6, preferably of the upwardly-tapering shape illustrated and terminating at its upper end in a constricted neck portion 7, rises from a base 8 on feet 9, 40 provided with casters 10, to adapt the appliance to stand upon and be readily moved over the floor. On the standard at a convenient height and adjacent to an opening 11 therein is rigidly supported, as by a brace-bar 12, a bracket 13, provided on one end with a bearing 14 for a horizontal shaft and terminating at its opposite end in a bearing 15 for a vertical member hereinafter described, this last-named bearing being between curved fingers 16, 16, adapted to embrace between them the standard, to which they are fastened at openings 17 through the medium of bolts 18. With the bracket fas-

tened in position the bearing 15 lies centrally within the standard 6, and the bearing 14 coincides with the opening 11. A shaft 19 is journaled in the bearing 14 and carries at its outer end a crank-handle 20 and on its inner end a miter-gear 21, which thus is within the standard and meshes with a similar gear 22, 50 journaled in the bearing 15 at its hub extension 23, this gear and its hub extension being internally screw-threaded. A post 24 extends downward into the standard 6, wherein it finds a guide-bearing in the neck portion 7, 55 that part of the post which is within the standard being screw-threaded to work in the interior screw-thread of the gear 22, through which it passes, and being also provided with a longitudinal groove 25, engaged 60 by a pin 26, extending into it from the standard to prevent the post from turning. From the upper projecting end of the post extends a gooseneck 27 carrying on its end a pendent bail 28, pivoted to adapt it to turn in a horizontal plane, and between the lower ends of the bail is pivoted the electromagnet 29 to adapt it to be turned in a vertical plane. The electromagnet shown is of a common construction adapting it to be used for the surgical purpose referred to and does not, therefore, require to be particularly described in this connection. It is connected from its binding-posts by wires 30 and 31 with a suitable electric switch (represented at 32) on the standard 6 and from which extends a suitable cable 33, terminating in a plug 34, adapted to be inserted into the socket of an incandescent electric lamp for supplying current through the switch to the electromagnet to 70 energize the latter.

The post 24, with its extension 27, affords an adjustable carrier for the magnet 29.

To use my improved appliance, it may be rolled on its casters to the operating-table or other support upon which the patient is laid, and its construction adapts it to be brought readily into any desired position relative to the patient, thus avoiding any requirement for positioning the patient with relation to it, 80 which is liable to be not only inconvenient but otherwise undesirable. With the appliance thus brought into position the operator by turning the handle to drive the intermeshing gears effects raising or lowering of 85 the threaded post 24, according to the re-

quirement and the direction of turning the handle, and with the pointed projecting core end 35 presented to the eyeball of the patient the adjustment thereof into required close proximity may be accomplished by the operator in turning the crank-handle with such extreme accuracy and nicety as to avoid danger of contacting the magnet with the eye-ball.

10. What I claim as new, and desire to secure by Letters Patent, is—

1. In a surgical eye-magnet appliance, the combination of a standard, a threaded magnet-carrier working in the standard, gear mechanism engaging with the threaded carrier for raising and lowering it, and an electromagnet adjustably supported on said carrier, for the purpose set forth.

2. In a surgical eye-magnet appliance, the combination of a standard, a threaded magnet-carrier non-rotatably working in said standard, gear mechanism engaging with the threaded carrier for raising and lowering it, and an electromagnet adjustably suspended on said carrier, for the purpose set forth.

3. In a surgical eye-magnet appliance, the combination of a portable standard, a bracket on the standard having journaled in it a shaft carrying on its outer end an operating-handle and on its inner end a miter-gear, a second miter-gear journaled on said bracket to mesh with said first-named gear and screw-threaded internally, a magnet-carrier comprising a threaded post passing through said threaded gear to engage with the threads of the latter, and confined against rotation, an extension on the upper end of the post, and an electromagnet adjustably supported on said extension, for the purpose set forth.

4. In a surgical eye-magnet appliance, the combination of a portable hollow standard containing an opening, a bracket on the standard having journaled in it a shaft carrying on its outer end an operating-handle and on its inner end a miter-gear, a second miter-gear journaled on said bracket within the standard to mesh with said first-named gear and screw-threaded internally, a magnet-carrier comprising a threaded post passing through said threaded gear to engage with the threads of the latter, and confined against rotation, an extension on the upper end of the post, and an electromagnet adjustably supported on said extension, for the purpose set forth.

5. In a surgical eye-magnet appliance, the combination of a hollow standard on a base provided with caster-equipped feet and terminating at its upper end in a neck portion, a bracket on said standard having journaled in it a shaft carrying on its outer end an operating-handle and on its inner end a miter-gear, a second miter-gear journaled on said bracket within the standard to mesh with said first-named gear and screw-threaded internally, a magnet-carrier comprising a screw-threaded post passing through said threaded gear to engage with the threads of the latter, and confined against rotation, a gooseneck extension on the upper end of the post, and an electromagnet adjustably suspended on the end of said extension, for the purpose set forth.

JULIUS B. WANTZ.

In presence of—

W. B. DAVIES,
C. W. WASHBURN.
